United States Patent Office

Des. 199,913
Patented Dec. 29, 1964

199,913

CLOCK

Benjamin Levy, 1703 Exeter Road,
Hewlett, Long Island, N.Y.

Filed June 29, 1964, Ser. No. 80,610

Term of patent 7 years

(Cl. D42—7)

FIG. 1

FIG. 3

FIG. 2

FIGURE 1 is a front elevational view of a clock, showing my new design;

FIGURE 2 is a rear elevational view thereof; and FIGURE 3 is a top plan view thereof.

I claim:

The ornamental design for a clock, as shown.
